UNITED STATES PATENT OFFICE.

HENRY M. NORTON, OF CHESTER, CONNECTICUT.

DESIGN FOR AN ICE-SHAVER.

SPECIFICATION forming part of Design No. 27,947, dated December 7, 1897.

Application filed August 27, 1897. Serial No. 649,783. Term of patent 7 years.

To all whom it may concern:

Be it known that I, HENRY M. NORTON, a citizen of the United States, and a resident of Chester, in the county of Middlesex and State 5 of Connecticut, have invented a new and original Design for Ice-Shavers; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a front view of 15 my invention, and Fig. 2 is an edge view of the same.

This invention has relation to a certain new and original design for ice-shavers.

The leading features of the design consist 20 in the shaver-blade, of broad flat form, having parallel faces, parallel lateral edges, and a double beveled cutting-edge portion, a

shank portion having symmetrical incurved lateral edges, a tapered handle portion, and a ferrule portion having a convex or rounded 25 end.

In the accompanying drawings the letters *a a* designate the parallel broad flat faces of the blade, *c c* its parallel lateral edges, and *b* its double beveled cutting-edge portion. *B* 30 designates the shank portion, having the incurved lateral edges *h*. *C* designates the tapered handle portion, and *F* is the ferrule portion.

Having thus described my invention, what 35 I claim as new is—

The design for an ice-shaver substantially as herein shown and described.

In testimony whereof I affix my signature in presence of two witnesses.

HENRY M. NORTON.

Witnesses:

JAMES PHELPS,
JAMES L. PHELPS.
